HEAT INTERCHANGER

William F. Giauque, Berkeley, Calif., assignor, by
mesne assignments, to Research Corporation,
New York, N. Y., a corporation of New York

Application September 25, 1945, Serial No. 618,439

4 Claims. (Cl. 257—229)

1

This invention relates to heat interchangers, and is concerned more particularly with heat interchangers constructed to obtain efficient heat transfer without excessive pressure drop.

It is a general object of the invention to provide an improved heat interchanger adapted for use with fluids that will provide a high heat transfer by providing uniform flow conditions for both of the fluids passing through the heat interchanger.

Another object of the invention is to provide an improved heat interchanger in which a large area of heat interchange surface is provided within a relatively small total volume of the interchanger.

Another object of the invention is to provide a heat interchanger of high efficiency which is easy to manufacture by commercial manufacturing processes.

Other objects and advantages of the invention will be apparent from the following description of the preferred embodiment thereof as illustrated in the accompanying drawings, in which:

Figure 1 is an elevational view of a heat interchanger embodying the invention.

Figure 2 is a horizontal sectional view of the heat interchanger immediately below the upper manifold thereof, and taken as indicated by the line 2—2 in Figure 1.

Figure 3 is a horizontal sectional view of the mid portion of the heat interchanger showing the arrangement of the crossover of the tubes, the view being taken as indicated by the line 3—3 in Figure 1.

Figure 4 is a detailed elevational view of the spacing strip of the coils of the heat interchanger.

Figure 5 is a sectional view of the spacer strip taken as indicated by the line 5—5 in Figure 4.

Figure 6 is an enlarged fragmentary view illustrating a crossover arrangement of the inner group of tubes.

Figure 7 is an enlarged fragmentary view illustrating a crossover arrangement of the outer group of tubes.

Figure 8 is a fragmentary enlarged view, partly in section, of an end of a heat interchanger unit.

Figure 9 illustrates a typical heat interchange system employing heat interchangers of the character disclosed herein.

In the construction of heat interchangers one important factor is the arrangement and relative disposition of the heat exchange surfaces of maximum area to provide for a uniform flow of the fluids through the interchanger. Thus, it is important that the tubing employed to conduct the fluid in one direction be of uniform size and that

2

the length of paths provided in the various tubes be substantially equal in length. Correspondingly, for the fluid contacting the outer surfaces of the tubes, it is important that flow of fluid through the spaces between the tubes be maintained substantially uniform by providing a substantially uniform dimension between the tubing at all points throughout the interchanger with excellent opportunity for cross mixing of fluids between the inter-tubing spaces.

The above objects are attained in the instant invention by the use of conduits or tubes wound in helical layers, the interchanger unit being composed of several such helical layers having a tubing arrangement to provide a constant length of the several pieces of tubing used and to provide a desired predetermined spacing radially with respect to the layers of tubing and axially with respect to adjacent turns of a layer of tubing.

10 In order to obtain the same lengths of tubing in the various layers, in certain larger sizes of interchanger units, the layers may be made of an increased number of tubes wound per layer from the inside layer outward. With smaller inter-

15 changer units, the tubing which forms one layer, for example the outer layer of a group of tubing, through one-half of the interchanger, is crossed over midway of the length of the interchanger to form another layer, for example an inner layer

20 of tubing. As a specific example, an interchanger having a group of tubing wound in three layers of properly related average diameters will be pro-

25 vided, with the same length of path of fluid flow in all the passes of the group by effecting a cross-

30 over between the inner and outer layers at the mid point of the interchanger. The same results can be obtained with any desired number of layers of tubing in a group but it is preferred to retain the number of layers small to cause less

35 unbalance in the flow outside the tubes.

40 In interchangers operating at sufficiently high pressures so that a small pressure drop is not serious, it is preferred to use a crossover arrangement of the passes to enable the use of a reduced

45 number of tubes in parallel, and a consequent increase in heat transfer on the inside tube surface.

46 While in general and in the usual average or small size interchanger it is desirable to maintain a uniform spacing between the respective layers

50 of tubing, with a large interchanger the greater curvature of the inner layers will somewhat affect the flow outside of the tubes so that the spacing can be altered if desired to compensate for this

55 effect and to obtain a substantially uniform flow of the fluid outside the tubes.

The invention has been illustrated in connec-

tion with a small size interchanger of the type making use of crossovers between layers of tubing and with alternate layers wound oppositely to facilitate uniformity of heat transfer and cross mixing and to provide greater strength and rigidity. This type of interchanger also provides for a minimum number of tubes in parallel within a layer.

Referring to Figures 1, 2, 3 and 8, the heat interchanger includes a central post or support in the form of a pipe 10 around which two groups of heat interchange tubes 11 and 12 are provided within a casing 9, each group consisting of three layers of tubing. As the upper and lower halves of each group of tubing are similar, the detailed description of the construction of each group will be made with reference to the upper half thereof. As previously stated, each layer of tubing consists of a helical coil of tubing of uniform spacing. The inner group of tubing 11 includes an inner layer 11a, an intermediate layer 11b and an outer layer 11c, which are wound in the present instance with two tubes in parallel. The inner layer 11a is disposed about the pipe 10 and is spaced therefrom by an appropriate number of circumferentially spaced longitudinal spacer strips 13 which may be secured to the pipe 10 by soldering so that the inner layer 11a of tubing is spaced from the pipe 10 by the thickness of the spacer strips 13. The inner tubing layer 11a is also engaged by a plurality of spacer strips 14 (Figures 1, 2, 4 and 5) which serves to space the intermediate layer 11b from the inner layer 11a by the same amount as its spacing from the pipe 10. Each spacer strip 14 has a series of struck-out ears 14a which are spaced apart a distance equal to the outer diameter of the tubing and project inwardly between the adjacent turns of the inner tubing layer 11a so that the turns are spaced apart an equal amount by the ears 14a of the spacer strips. The ends 14b of the strips 14 as shown in Figure 8 are bent over to engage the end turns of the coil and the pipe 10 and are secured thereto by soldered joints. If desired, the strips 14 and the tubing 11a may be secured together in assembled relation by soldering at an appropriate number of points. The middle layer 11b and the outer layer 11c are similarly mounted and secured by spacer strips 14 having the ears 14a interposed between the turns thereof.

As previously explained, the upper and lower halves of the interchanger are similar and at the midpoint of the interchanger a crossover is effected between the inner and outer layers of the group while the intermediate layer remains in the same relative position. Referring to Figures 1, 3 and 6, it is seen that at the mid point of the interchanger the inner layer 11a of the upper half is connected by a soldered sleeve joint 15 to the tubing of the outer layer 11c of the lower half, while the tubing in the outer layer 11c of the upper half is similarly connected by a sleeve 15 to the tubing of the inner layer 11a of the lower half. The middle layer 11b of both the upper and lower halves are of the same diameter. In this way each of the layers 11a, 11b and 11c of the inner group are of the same length.

The outer group of layers 12 comprising an inner tubing layer 12a, a middle tubing layer 12b and an outer tubing layer 12c are similarly constructed and arranged as the tubing of the inner group, except that this group is wound with three tubes in a set to provide a greater helix pitch or lead. The other length of the tubing can be made equal to that of the inner group of tubes wound with two tubes at a time and a correspond-

ing lesser lead. The outer tube group 12 is similarly provided with spacers 14 having spacing ears 14a.

At the lower end of the heat interchanger the 5 six pieces of tubing of the inner group 11 and the nine pieces of tubing of the outer group 12 are connected to an annular manifold 17 which is connected to an inlet conduit or pipe 29. Similarly, at the top of the heat interchanger the 10 respective pieces of tubing are connected to an upper manifold 19 which is provided with an outlet conduit 31, to prevent undesired heat transfer because of a flow of fluid through the pipe 10. The pipe may be closed by means of a plug 21, 15 made of suitable heat insulating material.

Referring to Figure 9, a heat interchange system is shown employing a pair of heat interchanger units 10 and 10a connected in series and disposed within an insulating casing 22, this arrangement being of the type employed, for example, in the manufacture of liquid oxygen. Associated with the heat interchanger group comprising the heat interchanger units 10 and 10a is a forecooling refrigerant unit 23 and a fractionating column 24 both of conventional construction and illustrated herewith to show a complete system. There is also provided a source 26 of high pressure air which is connected to the lower heat interchange unit 10 through a conduit 27 to deliver high pressure air to the lower end thereof. 20 The air passes upwardly through the heat interchanger unit 10 and is withdrawn from the upper end of this heat interchanger unit through a conduit 28 connected to the refrigerating unit 23 where a further cooling of the air is effected. 25 The cooled air is brought back to the lower end of the upper heat interchanger 10a through a conduit 29. The discharge from the upper end of the unit 10a is provided through a conduit 31 which leads to the upper end of the fractionating column 24, the effluent from the top of the fractionating column 24 being returned through the pipe 32 to pass downwardly through the heat interchanger units 10a and 10 to cool the air within the tubes and to be discharged at the bottom 30 40 45 through a discharge elbow 33.

Operation

The operation of the heat interchanger will be described in connection with the system shown in Figure 9. From the above description it will be seen that high pressure air supplied through the inlet pipe 27 will travel upwardly through the tubing of the lower heat interchanger unit 10, being cooled by the downwardly traveling effluent from the fractionating column 24 which travels through the spaces between the layers of tubing. The partially cooled air is carried from the manifold 19 at the upper end of the lower heat interchanger unit 10 through the discharge pipe 28 to the forecooling unit 23 where it is subjected to refrigeration in the desired degree in accordance with the fluids being employed. The cooled air from the forecooling unit 23 is returned through the pipe 29 which conducts it to the manifold 17a at the lower end of the upper heat interchanger unit 10a where, as it travels upwardly, it is further subjected to cooling by the effluent passing downwardly through this heat interchanger. Preferably, the length of the heat interchanger is so selected with respect to the use for which it is intended so that the air will be cooled to the appropriate temperature for feeding through the discharge pipe 31 to the fractionating column 24 from which liquid oxygen can be obtained in the usual manner.

While the description of the unit and its mode of operation have been made in connection with the production of liquid oxygen, it will be apparent that the heat interchangers, such as units 10 and 10a, can be used singularly or in combination for any desired character of heat transfer at high or low temperatures with the heat transfer taking place between, on the one hand, a fluid traveling through the helical coils of tubing and, on the other hand, a fluid traveling 10 between the helical coils of tubing.

While I have shown and described a particular form of the invention, it will be apparent that the invention can be modified or employed in other forms without departing from the scope of the invention as defined in the claims appended thereto.

I claim:

1. In a heat exchanger, inlet and outlet manifolds spaced along a longitudinal axis, and a plurality of heat exchange tubes of substantially equal length and diameter having their ends connected to the manifolds, one group of said tubes being wound to form at least two helixes disposed end to end and on different diameters and with a crossover connection between the helixes, the two sets of helixes thus formed by such tubes being nested and concentric with the helixes of adjacent tubes, another group of said tubes being each wound to form at least two helixes likewise disposed end to end and on different diameters and with a crossover connection with the helixes, said last-named helixes being likewise nested concentric to each other and with respect to the helixes of the first-named tubes, each of the helixes formed by the tubes of the second group being formed by a number of tubes greater than the number of tubes forming the helixes of the first group of tubes whereby the lead of helixes formed by the greater number of tubes is greater than that of the helixes formed by the lesser number of tubes to obtain tubes of the same length in both groups.

2. In a heat exchanger, inlet and outlet manifolds spaced along a longitudinal axis, and a plurality of heat exchange tubes of substantially equal length and diameter having their ends connected to the manifolds, one group of said tubes being wound to form at least two helixes disposed end to end and on different diameters and with a crossover connection between the helixes, the two sets of helixes thus formed by such tubes being nested and concentric with the helixes of adjacent tubes, another group of said tubes being each wound to form at least two helixes likewise disposed end to end and on different diameters and with a crossover connection with the helixes, said last-named helixes being likewise nested concentric to each other and with respect to the helixes of the first-named tubes, longitudinal spacer strips between and contacting the tubes of said nested helixes and having laterally projecting ears extending between and contacting adjacent turns of each helix, each of the helixes formed by the tubes of the second group

being formed by a number of tubes greater than the number of tubes forming the helixes of the first group of tubes whereby the lead of helixes formed by the greater number of tubes is greater than that of the helixes formed by the lesser number of tubes to obtain tubes of the same length in both groups.

3. In a heat interchanger, a plurality of groups of conduits, each of said conduits having substantially the same length and diameter, each group comprising a plurality of sets of helically disposed similar conduits having a common helix axis and arranged in predetermined radially spaced relation, the conduits of each set forming a layer of the same helical radius and lead, at least two sets of conduits forming respective layers of a group at one end of the interchanger crossing over intermediate the ends of the interchanger to replace each other in the respective layers to provide conduits of substantially the same length in said sets, and the respective numbers of conduits in each group being related to each other and to the respective diameters of the groups of conduits to provide conduits of substantially the same length in said groups.

4. In a heat interchanger, a plurality of groups of conduits, each of said conduits having substantially the same length and diameter, each group comprising a plurality of sets of helically disposed similar conduits having a common helix axis and arranged in predetermined radially spaced relation, the conduits of each set forming a layer of the same helical radius and lead, the sets of conduits forming the extreme inner and outer layers of a group at one end of the interchanger crossing over intermediate the ends of the interchanger to form the opposite extreme layers of the group at the other end of the interchanger to provide conduits of substantially the same length in said sets, and the respective numbers of conduits in each group being related to each other and to the respective diameters of the groups of conduits to provide conduits of substantially the same length in said groups.

WILLIAM F. GIAUQUE.
